(57) CLAIM

The ornamental design for a toe crest, as shown and described.

DESCRIPTION

FIG. 1 is a front top perspective view of the present design for a toe crest;

FIG. 2 is a left side view of the toe crest of the design of FIG. 1;

FIG. 3 is a right side view of the toe crest of the design of FIG. 1;

FIG. 4 is a top view of the toe crest of the design of FIG. 1; FIG. 5 is a bottom view of the toe crest of the design of FIG. 1;

FIG. 6 is a front view of the toe crest of the design of FIG. 1;

FIG. 7 is a back view of the toe crest of the design of FIG. 1;

FIG. 8 is a bottom view of a top portion of the toe crest of the design of FIG. 1;

FIG. 9 is a top view of a spacer of the toe crest of the design of FIG. 1; and,

FIG. 10 is a bottom view of the spacer of the toe crest of the design of FIG. 1.

In the drawing, the broken lines show portions of the toe crest that form no part of the claim.

1 Claim, 6 Drawing Sheets
